UNITED STATES PATENT OFFICE.

CLOYD A. McILVAINE, OF BALBOA HEIGHTS, CANAL ZONE, PANAMA.

WRENCH.

1,403,334.

Specification of Letters Patent. Patented Jan. 10, 1922.

Application filed June 25, 1921. Serial No. 420,264.

To all whom it may concern:

Be it known that I, CLOYD A. McILVAINE, a citizen of the United States, and a resident of Balboa Heights, Canal Zone, Panama, have invented a new and Improved Wrench, of which the following is a full, clear, and exact description.

This invention relates to improvements in wrenches, an object of the invention being 10 to provide improved means for moving the movable jaw of the wrench so as to effectually grip the nut or permit a release of the same after the initial adjustment of the wrench is made.

15 It is a well-known fact that in the use of wrenches, even after the movable jaw has been adjusted, there is a slight play between the jaws and the nut to allow the wrench to be removed from the nut and take a new 20 hold. If the adjustment of the jaws is too tight, they must be released before the wrench can be released from the nut and this results in a loss of time. If the jaws are too far apart, the result is either an accidental 25 removal from the nut or an injury to the nut by slipping thereon, and it is the purpose of my invention to provide a wrench having a movable jaw and having means for controlling the movable jaw after adjustment 30 so as to permit a quick grip and release of the nut.

A further object is to provide a wrench with an improved construction and arrangement of thumb or finger lever which 35 operates as a cam to impart movement to the movable jaw and which may be locked in its extreme position to lock the jaws on the nut, as occasion may require.

With these and other objects in view, the 40 invention consists in certain novel features of construction, and combinations and arrangements of parts as will be more fully hereinafter described and pointed out in the claims.

45 In the accompanying drawings—

Figure 1 is a view in side elevation illustrating my improved wrench and showing the operating lever in one extreme position;

50 Figure 2 is a similar view partly in longitudinal section showing the lever in its other extreme and locked position;

Figure 3 is an edge view; and

55 Figure 4 is a view in transverse section on the line 4—4 of Figure 2.

Referring in detail to the drawings, 1 represents the shank of my improved wrench

which is provided with a fixed jaw 2 at one end and a handhold 3 at the opposite end. A movable jaw 4 mounted to slide on the shank is adjustable by a screw 5 journaled 60 in and extending through an abutment 6 fixed to the shank 1. A knurled nut 7 on the lower end of the screw 5 is normally held in spaced relationship to the under face of the abutment by a coiled spring 8 around the 65 screw between a shoulder 9 in the abutment and the nut 7.

It is obvious that the adjusting screw may be operatively connected to the movable jaw in any approved manner and in fact I do not 70 limit myself to any particular adjusting means as my invention is broad enough to cover any means for establishing the initial adjustment of the jaw.

A hardened metal disc 10 fits in the bottom 75 of a pocket 11 on the under face of the nut 7 and an annular groove 12 is formed in the under face of the nut around the pocket.

The handhold 3 is recessed, as indicated at 13 to expose the shank 1 which is formed 80 with a dove-tail groove 14 receiving a tenon 15 on a bifurcated bracket 16.

A lever 17 is pivoted adjacent one end in the bracket 16 on a pin 18 and a stud 19 extending inwardly through one arm of the 85 bracket cooperates with a slot 20 in the lever to limit the swinging movement thereof.

At its free end, the lever 17 is formed with a lateral extension 21 having a convexly curved cam face forming a continuation of 90 the curved face of the free end of the lever. This curved surface acts as a cam to move the jaw 4 longitudinally against the action of the spring 8 and is formed with a groove, 95 22 which serves as a runway or contact surface for a ball bearing 23 seated in the pocket 11.

The extension 14 may be accommodated in a recess 24 in the shank 1 when the lever is swung inwardly against the shank. A bow 100 spring 25 carried by the lever and engageable with the shank tends to hold the free end of the lever away from the shank. The lever, however, may be locked in inwardly swung position against the action of the 105 spring 25 by a sliding locking arm 26 mounted on the lever and engageable in the groove 12.

It will be noted that the particular means of securing the bracket 16 to the shank 1 110 firmly braces the bracket against strains transmitted from the movable jaw when the

wrench is used to turn a nut. The rolling contact between the screw and cam surface obviates the danger of the lever sticking when it is swung inwardly and permits a 5 rapid release of the wrench jaws from a nut.

The operation of the wrench is as follows: The screw 5 is utilized to adjust the movable jaw 4 to a position for normal engagement 10 with a nut. The operator then grasps the handhold 3 and engages the lever 17 with his fingers. By exercising a grip of his hand, he swings the lever 17 on the pin 18 causing the cam surface at the free end of the 15 lever to press against the ball 23, forcing the screw 5 and movable jaw toward the fixed jaw thereby securely gripping the nut and permitting an effectual turning thereof. When it is desired to take a new hold on 20 the nut, the pressure on the lever 17 is released, the jaws of the wrench removed from the nut and repositioned and the lever again gripped to cause the jaws to tightly grip the nut.

25 Whenever it is desired to grip the jaws in a fixed relation on the nut, the lever 17 is swung inwardly against the shank 1 and the arm 26 is moved into locking relation with the groove 12, as indicated in Figure 2. This 30 will permit the wrench to be swung or spun with the nut. It will be noted that the lever 17 and the handhold 3 constitute a combined grip so that the lever is sensitive to the movement of the fingers and the wrench can 35 be conveniently operated by one hand and quickly manipulated for all ordinary uses.

Although I have illustrated one of the preferred embodiments of my invention, it will be apparent that various slight changes 40 and alterations might be made in the general form and arrangement of the parts described without departing from the invention and hence I do not wish to limit myself to the precise details set forth, but shall consider 45 myself at liberty to make such slight changes and alterations as fairly fall within the spirit and scope of the appended claims.

I claim:

1. In a wrench, a shank, a fixed jaw at 50 one end of the shank, a movable jaw slidable on the shank, an abutment fixed to the shank, a spring held screw journaled in the abutment and operatively connected to the movable jaw for actuating the same, and means 55 having rolling engagement with the screw for moving said jaw against the action of the spring.

2. In a wrench, a shank, a fixed jaw at one end of the shank, a movable jaw slidable on 60 the shank, an abutment fixed to the shank, a spring held screw journaled in the abut-

ment and operatively connected to the movable jaw for actuating the same, and means engageable with the screw for moving said jaw against the action of the spring, said means including a pivoted lever having a cam face, and means providing a roller contact between said face and one end of the spring held screw. 65

3. In a wrench, a shank, a fixed jaw on 70 the shank, a movable jaw on the shank, an abutment fixed to the shank, a spring held screw extending through the abutment and operatively connected to the movable jaw, a bracket fixed to the shank, a lever pivoted 75 in the bracket and including a grooved cam face adjacent its free end, said screw having a pocket therein, a ball bearing in the pocket contacting with the grooved cam face.

4. In a wrench, a shank, a fixed jaw on 80 the shank, a movable jaw on the shank, an abutment fixed to the shank, a spring held screw extending through the abutment and operatively connected to the movable jaw, a bracket fixed to the shank, a lever pivoted 85 in the bracket and including a grooved cam face adjacent its free end, said screw having a pocket therein, a ball bearing in the pocket contacting with the grooved cam face, said shank being recessed to accommodate said 90 lever in its extreme position, means for locking said lever in its extreme position.

5. In a wrench, a shank, a fixed jaw on 95 the shank, a movable jaw on the shank, an abutment fixed to the shank, a spring held screw extending through the abutment and operatively connected to the movable jaw, a bracket fixed to the shank, a lever pivoted 100 in the bracket and including a grooved cam face adjacent its free end, said screw having a pocket therein, a ball bearing in the pocket contacting with the grooved cam face, said shank being recessed to accommodate said 105 lever in its extreme position, said screw having a groove therein around the pocket, a locking arm mounted to slide in the lever and engageable in the groove to lock the lever in its extreme position.

6. In a wrench, a shank, a fixed jaw at one 110 end of the shank, a movable jaw slidable on the shank, a handle on the shank, an abutment fixed to the shank, a spring held screw journaled in the abutment and operatively connected to the movable jaw for initially 115 adjusting the same, a lever pivoted at one end in the handle and including a cam surface at its free end, and means whereby swinging of the free end of the lever toward the handle further tightens the jaws against the action of the spring.

CLOYD A. McILVAINE.
